UNITED STATES PATENT OFFICE

WILLIAM HATTON, RANSOM D. SPANN, ERNEST J. ROUSSEAU, AND FRIDITHIOF O. V. LARSEN, OF PARIS, FRANCE, ASSIGNEES TO WESTERN ELECTRIC COMPANY, INCORPORATED, OF NEW YORK, N. Y., A CORPORATION OF NEW YORK

TELEPHONE SYSTEM

Application filed March 23, 1931, Serial No. 524,544, and in Great Britain June 6, 1930.

This invention relates to telephone systems, and particularly to telephone systems of the automatic or semi-automatic type.

The invention is particularly applicable to a telephone system in which a subscriber's line in a local exchange may either be connected to other subscribers' lines in said exchange or to junction lines incoming from or outgoing to a distant exchange; said connections being set up either under the control of or independently of an operator at the local exchange.

According to one feature of the invention a circuit arrangement is provided whereby subscribers in one exchange may extend a connection to or receive a connection from a distant exchange. The circuits for certain of said subscribers are provided with means which on the receipt of a connection for such a subscriber from a distant exchange or on the initiation of a connection from such a subscriber for extension over an outgoing junction line is operable to prevent such connection from being established, and which on the receipt of a connection from or on the initiation of a connection for a local subscriber is rendered inoperative.

According to another feature of the invention an arrangement is provided whereby a plurality of operators' circuits at the local exchange are so interconnected that any one of the operators has access to any free junction line, and whereby the seizure of a junction line by any one operator automatically prevents a connection from being made thereto by any other operator.

Another feature provides means whereby an incoming call may be extended to any one of a number of operators and whereby the different operators' circuits may be so inter-linked that only the one which extends the connection to the wanted line will receive supervisory signals for the particular call in progress.

Another feature provides means whereby a connection may be made between a subscriber's line in the local exchange and a junction line extending to or from a distant exchange either with or without the control of an operator and whereby if a connection

is extended from a junction line to a subscriber in the local exchange by an operator, the latter can prepare this connection and disconnect herself from the circuit, and thereby causes the connection to be completed automatically.

Another feature provides means whereby a distinctive signal may be displayed at the operator's position indicating that a connection is being extended between a junction line and a local subscriber, and this signal continues until the connection is completed after which the operator is prevented from re-entering the circuit. During the time that the connection is being established it is arranged so that when the local subscriber signals an operator supervisory signals are sent only to the particular operator who prepared the connection.

Another feature of the invention is that each operator at the local exchange is provided with a different number so that any particular operator can be reached from any subscriber in the exchange in a manner similar to that employed when a connection is extended to another subscriber in the same exchange.

A night attendant's position may be provided having all the facilities of an ordinary operator's position whereby any incoming call may be automatically extended to any desired subscriber in the exchange.

These and other features of the invention will be more completely understood from the following detailed description which is given in conjunction with the accompanying drawings, in which:

Fig. 1 shows four subscribers' line circuits;

Fig. 2 shows two of a number of links circuits and portions of two of a number of junction line circuits;

Fig. 3 shows a register circuit; and

Fig. 4 shows one of a number of operators' positions and the remaining portion of one of the junction line circuits shown in Fig. 2.

This figure also shows two groups of relays individual to other operators' positions in other junction line circuits. These figures may be arranged as shown in Fig. 5.

Each link circuit comprises relays Plr,

Pr, *Mr* and *Nr*, and each subscriber's line is provided with a relay *Lr* and one *Cr* relay for each link circuit.

In the embodiment shown in the drawings the circuits are arranged for a private automatic branch exchange and while the invention is mainly applicable to this type of exchange it is to be understood that it is not exclusively limited to an exchange of this character.

Referring now to the drawings, when a subscriber removes his receiver, his line relay *Lr* will be operated over the loop, provided the register circuit is free.

Lr, when operated, closes the holding circuit in series with relay *Tr* in the register circuit.

Tr operates and when it leaves its back contact removes the common starting ground at *Har*, making the circuit busy for other calls.

Over its front contact a ground is closed for the operation of slow relay *Sr*. *Sr* connects a direct ground, provided the back contact of the thermostatic relay *Har* is made for the operation of *Pr* in the first free link circuit. *Pr* operates and locks to the same ground, and opens the energization circuit for all the other *Pr* relays in the different link circuits.

Over a front contact of the operated *Pr* relay the energization circuit is closed for the operation of the *Plr* relays in the corresponding link, which connect a direct ground to the holding contact of relay *Lr* and short circuit *Tr* which again releases *Sr*. At the same time a direct battery is connected through the windings of the *Cr* relays causing the operation of the *Cr* relay which corresponds with the already operated *Lr* relay.

The *Cr* relay connects the A lead of the subscriber's line over the back contact of *Mr* to a direct ground and the B lead through winding to battery of *Ir*.

Ir operates and over its front contact causes the operation of slow releasing relay *Or* which in turn, operates its helping relay *Ar*.

Ar relay opens the energization circuit for *Plr*, which releases the *Lr* relay. *Ar* also connects a direct ground to hold the *Pr* relay, and over the back of *Rer* and *Lrm* a ground is supplied to the tone relay *Tor*.

Tor furnishes the dialing tone through a small condenser $\frac{1}{10}$ mf. to the B lead to notify the subscriber to dial the desired number.

Over a back contact of *Ar* the common starting ground is removed.

Over a back *Ir* and a front of *Ar*, the stepping lead is connected to the *Sm₁* switch in parallel with the slow releasing relay *Lmr* which operates on the first impulse and remains operated during the train of impulses.

After the end of the dialing *Lmr* releases and, provided the back contact of the thermostatic relay *Hbr* is made, causes the operation of relay *Er* which locks up under the control of the ringing trip relay *Rgr*. *Er* relay operated, causes the release of slow releasing relay *Sr* which, for a short moment, connects a direct ground over its front contact and front contact of *Er* through the winding of test relay *Tr* to the selected subscriber's line relay *Lr* to operate this relay.

Tr also operates causing the operation of *Rer* from the momentary ground at *Sr*.

Tr and *Rer* lock to *Ar* and *Rer* connects a direct ground to the holding contact of the operated *Lr* and to the outgoing B lead.

Over a second front of *Rer* a direct ground is connected to the ringing pulsing relays *Xr* and *Yr*.

The thermostatic relay *Hbr* energizes with a ground supplied over front of *Er* relay, this relay is adjusted to close its front contact in a minimum time of 6 seconds.

The ringing current is fed from the ringing transformer through the ringing trip relay *Rgr*, over front contact of *Rer* and *Lr* to the desired subscriber's A lead.

When the subscriber answers, *Rgr* operates and opens the holding circuit for *Er* which releases and over its back and a front of *Rer* causes the operation of relay *Mr* in the link circuit.

In parallel with *Mr* the ground is supplied over front of *Ar* to the *Plr* relays which operate and cause the operation of relay *Cr* of the desired subscriber's line in the corresponding link circuit.

Relay *Cr* connects the desired subscriber's line in parallel with the calling subscriber to the common supervisory relay *Nr*, over the front contacts of *Mr*. When *Mr* operates the path is opened for relay *Ir* which releases in turn, releasing *Or* and *Ar*.

Relay *Ar* opens the common holding ground for the register circuit releasing *Tr*, *Lr*, *Rer* and over its back closes the restoration circuit for the *Sm₁* switch.

If after the time from 6 to 8 seconds the desired subscriber should not answer, thermostatic relay *Hbr* will close its front contact and cause the operation of relay *Mr* which connects the desired subscriber to the link circuit and frees the register circuit in the manner already described. If the subscriber should answer later the circuit is ready for conversation.

When, after the conversation both subscribers hang up relay *Nr* releases in turn releasing relay *Mr* which removes the holding ground from the operated *Cr* relays which release and bring the link circuit back to its normal position.

If the wanted party has been engaged, then one of his *Cr* relays would have been oper-

ated; the T_r relay would not operate, therefore, when the slow releasing relay S_r falls back, the ground for test is removed.

Over front contact of E_r and back of R_{cr} a ground is fed for the T_{or} relay which furnishes the busy tone of the calling subscriber's line who, when hanging up releases the circuit. Relay H_{br} operates in the same manner as described before and will free the register if the subscriber does not hang up before the time of operation of H_{br} .

Should a subscriber not dial in a time of 20 to 30 seconds after receiving the dialing tone relay H_{ar} has time to make its front. This relay also causes the operation of M_r which frees the register circuit leaving the link circuit busy until the subscriber hangs up or the loop is removed from the line.

The circuit shows in dotted lines the additional equipment necessary for 20 lines.

The circuit operates in a similar manner as described for 10 lines, to the end of the first digit. When L_{mr} falls back the ground is supplied over the S_{m_1} switch to the armature and normal contact of S_{m_2} to winding and battery of T_{er} .

T_{er} operates and locks to the same ground and over the change-over contact the stepping lead is transferred from winding of S_{m_1} to S_{m_2} .

The next series of impulses will be received on S_{m_2} .

After the end of selection L_{mr} falls back causing the operation of relay E_r . The further operation of the circuit is from this moment similar to that already described for 10 lines.

With the arrangement shown the subscribers may be distributed into four different classes of service.

(a) Unrestricted service.

This class of subscriber has all the facilities of the city service. This means that he may call the city automatically or with the help of one of the attendants and he may also receive calls incoming from the city exchange.

(b) Restricted out service.

This means that this class of subscriber can only by the help of the attendant, but not automatically get connected to the city exchange, but he has a facility for receiving calls incoming from the city.

(c) Restricted in service.

This subscriber has the facility of calling automatically out to the city but he will not be able to receive any call from the outside.

(d) Restricted in and out service.

This subscriber is restricted to only local service and is totally debarred from making calls outside the P. A. B. X.

For outgoing calls to the city exchange the P. A. B. X. subscriber will first dial a prefix which may be "0" giving the subscriber

who has unrestricted and restricted service access to a number of junction lines.

The distinguishing between the unrestricted and restricted out subscribers is given in the register circuit by the operation of one relay R_{sr} which operates over the locking path of relay L_r of the out restricted subscriber's line circuit.

R_{sr} opens the test lead for the junction lines, therefore these subscribers, by dialing "0" will receive busy tone.

The register and the link circuit will be picked up and operated in the same manner as already described for local calls.

When the first digit, which we decided to be "0" has been received the S_{m_1} switch will stop on the terminal 10. The a leads shown on arcs of the S_{m_1} switch is therefore connected to this terminal.

When L_{mr} falls back the ground is supplied over its back contact and arc 2 of S_{m_1} for the operation of E_r which locks and closes the test circuit as already described.

T_r is connected to arc 4 S_{m_1} , back R_{sr} and over the change-over contact of J_{br} and J_{ir} to the line relay J_{lr} of the first free junction circuit.

T_r operates in series with J_{lr} and closes the operating path for relay M_r and P_{lr} over arc 3 of S_{m_1} .

Relay M_r causes the release of the register circuit.

P_{lr} causes the operation of the proper J_{cr} relay connecting the subscriber's line metallic through the junction line to the city exchange where it makes a call in the well known manner causing the operation of supervisory relay J_{sr} in the junction circuit. There is provided one J_{cr} relay for each link circuit in each junction line circuit.

J_{lr} causes the operation of relay J_{br} which makes the junction line circuit busy.

If all the junction lines are busy S_r falls back removing the earth from the winding of the test relay T_r wherefore busy tone is given back to the subscriber.

J_{sr} operates in response to the connecting up of the junction line and in turn J_{mr} is operated which opens the energization path for the thermostatic relay J_{tr} and operates J_{br} to transfer the station wire to the next idle junction line.

Relay M_r in the link circuit is held operated over front contacts of J_{cr} making the link circuit busy for other calls.

The release of the junction is effected from the P. A. B. X. subscriber who, when he hangs up, releases the J_{sr} and J_{mr} relays.

J_{mr} closes the energization path for J_{tr} . This relay is adjusted to open its back contact after a time from 5 to 8 seconds.

J_{tr} removes the holding earth from the circuit causing the release of the junction and link circuit relays and freeing the P. A. B. X.

subscriber. It must be noticed that for this service, no signal is given to the attendant.

As previously stated the P. A. B. X. subscriber having unrestricted or restricted out service, (a or b) instead of dialing up the connection himself may call the operator locally and request her to set up the connection to the city exchange and then re-ring him. One operator's position is shown at A, Fig. 4. Other similar operators' positions will be connected up over the contacts of other *Jnr* and *Jor* relays.

The manner in which an operator sets up the connection and then recalls the P. A. B. X. subscriber will now be described.

The P. A. B. X. subscriber calls one of the attendant's local numbers in the same manner as he would call another subscriber as each attendant is equipped with the same circuit arrangement as the subscribers. The bell on the attendant's set rings whether the receiver is on the hook or not. This means that if the attendant should be busy on a city connection she will always know the arrival of a local call.

If she is busy on a city connection she may depress the corresponding junction holding key *Hk* and then depress the key *Lok* which closes the circuit for the local line to the telephone set through leads *AT*.

Lok opens the circuit for the buzzer making the attendant able to control the service of all incoming calls without being disturbed by the noise of the buzzer, the P. A. B. X. subscriber gives her the name and number of the desired city subscriber and his own name and number in the usual manner.

The P. A. B. X. subscriber may now hang up and wait for the re-ring.

The attendant restores *Lok* and can now set up the city connection straight away.

One of the junction line keys is depressed to its position *Hk*. If the junction line is free the signal comes on, wherefore the attendant moves the key back to its after position *K* making the junction line busy and connecting her telephone set through to the city exchange where the connection is set up in the usual way.

If the junction is free when *Hk* is thrown, a ground is connected over its front and back *Jnr* and *Jbr* to winding of *Jir* causing this relay to operate and lock to the common holding ground supplied over the back of the thermostatic relay *Jtr*. *Jir* closes the circuit for the signal on the attendant set with a direct battery from back *Jer*, front *Jir* back of all *Jnr* relays through winding of all *Jor* relays and the signals to ground in the attendant's telephone set.

Relay *Jor* is not able to operate in this circuit.

The signal when operated closes the circuit for the buzzer. Over a front contact,

the attendant moves the junction key to its position *Lk*.

Lk opens the circuit for the signal and connects a direct ground for the operation of the relay *Jor* which corresponds to this attendant.

Jor connects the A and B leads from the attendant's set through the junction line circuit to the city exchange where it makes a call in the well known manner.

Over a second front contact of *Jor*, the circuit is closed for *Jnr* which operates and locks over its own front contact and the back of *Jrr* to the same ground.

Jnr opens the operating path for all other *Jor* relays in the same junction line, therefore the first attendant who depresses the junction key is individual to this junction and only this attendant can handle and get the supervision of this junction call.

Relay *Jsr* operates over the loop to the city exchange in turn operating its helping relay *Jmr* which again closes the energization circuit for *Jbr*.

As already noted when either *Jbr* or *Jir* relays are operated the junction is made busy and the test lead from the register circuit is therefore transferred over the front contact of one or both of these relays to the next junction circuit.

When the attendant is in communication with the wanted city subscriber she may re-ring the P. A. B. X. subscriber. The circuit will be handled in a similar way as an incoming call and will be further described under this paragraph.

On an incoming call ringing current is originated from the city exchange causing the operation of *Jwr*. This in turn connects a direct ground for the operation of *Jir* which, as already described, connects over its front contact a direct battery for the operation of all the signals corresponding with this junction.

The first attendant who depresses the corresponding key *Lk* will remove the signal from the other attendant and be connected to the city subscriber and therefore be responsible for the service of this call. The city subscriber gives her the name and number of the P. A. B. X. subscriber.

The circuit will now stand in exactly the same position as when the operator wants to re-ring the P. A. B. X. subscriber after having originated an outgoing call, therefore the circuit operation is from this point the same for both cases.

The first operation for the operator is to be connected to the P. A. B. X. register circuit. This is done by depressing the common key to its non-locking position shown as *Rk*. This key connects a direct ground over its front contacts and the front contact *Jor* to the winding of *Jkr*. If no other *Jkr* relays are operated at the time, the battery is con-

nected to the winding of J_{kr} causing this relay to operate.

J_{kr} connects its left-hand front contact to direct battery to complete a circuit over the back of J_{ar} to the lower winding of J_{lr} and ground. If the register circuit is free J_{lr} operates and causes the operation of Tr in the register circuit which starts the circuit hunting for a free link as on an ordinary 10 call.

J_{lr} closes over its front contact the energization path for R_{ir} . This relay opens the lead to arc 5 of Sm_1 . This arc carries all restricted in subscribers, therefore, the test 15 lead to those subscribers is open and all calls originated over the junction circuit to this subscriber will test busy.

Relays Pr and Plr in the free link circuit operate in the manner already described 20 causing the operation of J_{er} in the corresponding junction line circuit.

Over front contact of J_{er} a direct ground is passed over front and J_{kr} to the winding and battery J_{dr} .

25 J_{dr} operates and connects the holding circuit for J_{kr} in series with relay J_{er} . In this position of the circuit the attendant will receive dialing tone wherefore she will release R_k and dial the number of the wanted P. A. B. X. subscriber.

The stepping circuit is closed as follows:

Earth, front J_{dr} , back J_{pr} , front J_{or} , attendant telephone set, front J_{or} , back J_{pr} , front J_{dr} , J_{er} , back M_r winding and battery of Ir .

40 The operation of the register circuit is exactly the same as described for local calls and the circuit will advance to the position where the desired subscriber is thrown over to the same link circuit as the attendant. J_{dr} has in the meantime connected the city subscriber to a resistance loop.

When Pr in the link circuit releases, the operating path for J_{dr} is removed causing 45 the release of this relay. J_{dr} in turn releases J_{kr} and over back closes the operation circuit for J_{ar} as follows:

Battery; front J_{er} , back J_{dr} , winding 50 J_{ar} to earth over front contact of J_{nr} , causing the operation of J_{ar} . J_{dr} , when falling back connects the city subscriber back to the attendant's telephone set. Over front of J_{ar} the P. A. B. X. subscriber's line is connected to the winding of supervisory relay J_{rr} .

55 If the P. A. B. X. subscriber is on, the relay J_{rr} operates closing over its front contact the operating path for J_{pr} . This relay connects the city subscriber back to the resistance loop and the attendant's line to the winding of J_{rr} in parallel with the P. A. B. X. subscriber.

If the P. A. B. X. subscriber decides to take this city connection the attendant restores the junction line circuit to its normal position, causing the release of J_{or} . This

relay opens the locking lead for J_{nr} which releases in turn releasing relays J_{ar} , J_{pr} and J_{rr} , connecting the P. A. B. X. subscriber with the city subscriber.

The conversation is from this moment absolutely secret and no attendant will be able to interfere with the connection unless the P. A. B. X. subscriber should wish to call an operator by means of flashing.

When the P. A. B. X. subscriber hangs 75 up, the series supervisory relay J_{sr} and its helping relay J_{mr} fall back starting the energization of the thermostatic relay J_{tr} which operates and when it opens its front contact releases the common holding ground from the circuit, causing all the operated relays to release.

If the P. A. B. X. subscriber should want one of the attendants to come back to the junction line circuit he may hang up his 85 receiver for a short moment and then remove it again causing the signal and buzzer to operate on the attendant's set.

This operation takes place as follows:—

When the P. A. B. X. subscriber hangs up 90 the receiver, relays J_{sr} and J_{mr} in the junction line circuit release and over back of J_{mr} the following circuit is closed, battery, front J_{er} , back J_{mr} , winding J_{fr} , back J_{ar} , front J_{br} to ground. J_{fr} operates and locks to 95 the same battery.

When the subscriber again removes the receiver from the hook, J_{mr} operates again and transfers the battery, front J_{mr} , J_{fr} and J_{ir} , back of J_{nr} , windings J_{or} to the signal in the operator's position.

One of the attendants depresses the key 100 L_k , causing the operation of the particular J_{or} and J_{nr} relays which again opens the circuit for all the signals.

J_{nr} causes the operation of J_{ar} which connects the P. A. B. X. subscriber to the winding of J_{rr} . This relay operates and causes the energization of J_{pr} , which connects the city subscriber back to the resistance loop 110 and the P. A. B. X. subscriber direct to the attendant. The attendant is now in connection with the P. A. B. X. subscriber who can, when she wishes, break down the existing connection and be transferred back to the main subscriber, where she has the possibility of setting up a new connection with another P. A. B. X. subscriber.

Either if the P. A. B. X. subscriber has hung up his receiver or not the attendant 120 may release the circuit by depressing the R_k which as before described, operates the corresponding J_{kr} if no other J_{kr} relay is operated.

Owing to the fact that J_{ar} is operated the 125 operation circuit of J_{lr} is opened and the holding ground for relays J_{er} , C_r and J_{er} is removed causing the release of those relays and making the link circuit free.

When the attendant restores R_k , J_{kr} re- 130

leases causing the release of Jar , Jpr and Jrr and the attendant's telephone set is again transferred back to the city subscriber.

It will be noted that the circuit now stays in exactly the same position as before, the attendant has connected the call to the P. A. B. X. subscriber, wherefore, she again may operate Rk . The register circuit will now be seized and the operator could now set up a new connection in exactly the same manner as before described.

The attendant does not need to wait for the answer of P. A. B. X. subscriber, she may, on a call as soon as selection is finished and she has received the ringing tone, depress the junction line key to its second position Hk bringing the signal back for supervision. The signal will stay until the P. A. B. X. subscriber answers.

It must be noted that no buzzing is given and only the signal corresponding with this attendant set is operated.

The circuit operation is as follows:

A direct ground is connected over front of Hk , Jnr , winding and battery of Jpr , causing the operation of this relay which as already noted connects the city subscriber to the resistance loop and the P. A. B. X. subscriber's line to the winding of Jrr . The holding earth for Jor is removed over back contact of Jpr causing the release of this relay, bringing the signal to operate on this attendant's set with a battery supplied over front contact of Jnr .

Jnr is now locked up over its own front contact and the back contact of Jrr , the circuit will stay in this position until the P. A. B. X. subscriber takes off the receiver.

On the answer from the P. A. B. X. subscriber Jrr operates causing the release of Jnr , which removes the battery for the signal and releases Jar and Jpr and connects the P. A. B. X. subscriber direct to the city subscriber.

Should the P. A. B. X. subscriber not answer, the signal remains operated and the attendant has always the possibility of being connected back to the city subscriber, as follows:

The junction key moves to its position called Lk , causing the operation of Jor in the junction line circuit.

Jor opens the locking ground for Jpr which then releases and connects the city subscriber over front contact of Jor back to the attendant.

In this position there is a possibility of breaking down the existing connection and making a new call as previously described.

The release of the junction from the attendant is done by releasing the junction line key to its normal position and hanging up the receiver. When the signal disappears the junction line is released.

When the attendant restores the key to its

normal position Jor is still held operated with a ground supplied over front Jmr , back Jpr and winding to battery over front of Jor .

When the attendant hangs up the receiver, Jsr and Jmr release causing the release of Jor and start the operation of Jtr . Jtr opens the holding ground for the junction circuit and brings this circuit back to its normal position.

It must be noted that an originated call from the attendant, either to a city or P. A. B. X. exchange, is controlled over the loop of the attendant's telephone set, therefore the release of the register circuit in both cases can be effected by hanging up the receiver for a short period of time. By removing the receiver again, a new call is originated to the register circuit.

By depressing Lok , the attendant's telephone set can be made to work as a local subset only.

The signals will always operate on all incoming calls, but no buzzing will be given. Owing to the fact that very few wires extend to the attendant's telephone set this may be transportable, and by means of a plug, may be arranged and connected up in any desired position.

This facility is therefore particularly applicable to night service, since it enables the incoming calls to be received by a night attendant who may extend such calls to any subscriber's line as desired.

What is claimed is:

1. In a telephone system, a local exchange, a distant exchange, subscribers' lines in said local exchange, means for interconnecting any two subscribers' lines, means for extending connections to and receiving connections from the distant exchange, means associated with said subscribers' lines operable on the receiving of a connection from the distant exchange intended for any one of certain subscribers' lines for preventing said connection from being completed, and means for preventing said last-mentioned means from interfering with connections to any one of said certain subscribers' lines from any other subscribers' lines.

2. In a telephone system, a local exchange, a distant exchange, subscribers' lines terminating in said local exchange, means for interconnecting any two subscribers' lines, means for extending connections towards the distant exchange from subscribers' lines, automatic stepping switches, means whereby said automatic stepping switches are momentarily actuated by the means for interconnecting any two subscribers and the means for extending connections towards the distant exchange from subscribers' lines to aid in the establishing of said connections, means associated with certain of said subscribers' lines operable on the initiation of connections from said certain subscribers' lines intended

for extension to the distant exchange for preventing such connections from being established, and means for preventing said last-mentioned means from interfering with connections from any one of said certain subscribers' lines to any other subscriber's line.

3. In a telephone system, a local exchange, a distant exchange, subscribers' lines terminating in said local exchange, means for interconnecting any two subscribers' lines, means for extending connections to and receiving connections from the distant exchange, means associated with certain subscribers' lines operable on the initiation of a connection from said distant exchange intended for any one of said certain subscribers' lines for preventing said connection from being completed, and operable on the initiation of connections from any one of said certain subscribers' lines intended for extension to the distant exchange for preventing such connections from being established, and means for preventing said last-mentioned means from interfering with connections to any one of said certain subscribers' lines from any other subscribers' lines, and from any one of said certain subscribers' lines to any other subscribers' lines.

4. In a telephone system, a local exchange, a distant exchange, subscribers' lines in said local exchange, subscribers' lines terminating in said local exchange, circuit means in said local exchange for extending connections to and receiving connections from said distant exchange, a relay device associated with each of certain subscribers' lines operable on the reception of a connection from the distant exchange intended for any one of said certain subscribers' lines for controlling said circuit means to prevent said connection from being completed.

5. In a telephone system, a local exchange, a distant exchange, subscribers' lines terminating in said local exchange, two switching devices in said local exchange, means including one of said switching devices for extending connections to certain of said subscribers' lines from other subscribers' lines, means including the other of said switching devices for extending connections to other subscribers' lines from said local exchange, and a relay device operating in response to incoming connections intended for said certain subscribers' lines for preventing such connections from being completed by the associated switching device.

6. In a telephone system, a local exchange, a distant exchange, subscribers' lines terminating in said local exchange, means for interconnecting any subscriber's line, means in said local exchange for extending connections towards the distant exchange from subscribers' lines, automatic stepping switches, means whereby said automatic step-

ping switches are momentarily actuated by the means for interconnecting any subscriber's line and the means for extending connections towards the distant exchange from subscribers' lines to aid in the establishing of said connections, a relay device operable on the initiation of a connection from any one of certain subscribers' lines intended for extension to the distant exchange, a busy signal device for said subscribers' lines, a means controlled by the operation of said relay device for transmitting a busy signal from said device to a call originating subscriber's line and for preventing the extension of a connection to the distant exchange from said call originating subscribers' lines.

7. In a telephone system, a local exchange, a distant exchange, junction lines between said exchanges, subscribers' lines terminating in said local exchange, means for interconnecting any two subscribers' lines, means for connecting a subscriber's line with a junction line, automatic stepping switches, means whereby said automatic stepping switches are momentarily actuated by said means for interconnecting any two subscribers' lines and means for connecting a subscriber's line with a junction line to aid in the establishing of said connections, a plurality of operators' positions, means for connecting an operator's position to any free junction line, and means responsive to the establishing of a connection to a free junction line for preventing a connection being made to said junction line from any other operator's position.

8. In a telephone system, a local exchange, a distant exchange, junction lines between said exchanges, subscribers' lines terminating in said local exchange, means for interconnecting any two subscribers' lines, means for connecting a subscriber's line with a junction line, automatic stepping switches, means whereby said automatic stepping switches are momentarily actuated by said means for interconnecting any two subscribers' lines and means for connecting a subscriber's line with a junction line to aid in establishing of said connections, a plurality of operators' positions, means for connecting an operator's position to any free junction line, means responsive to the establishing of a connection to a free junction line for preventing a connection being made to said junction line from any other operator's position, and means individual to each operator's position and responsive to an attempt from an operator's position to seize junction lines for indicating whether said junction line is idle or busy.

9. In a telephone system, an exchange, subscribers' lines terminating in said exchange, operators' positions, junction lines terminating in said exchange means for establishing

connections from a junction line to a subscriber's line by the aid of the operator at any one of said positions, automatic stepping switches, means whereby said automatic stepping switches are momentarily actuated by said means for establishing connections from a junction line to a subscriber's line to aid in the establishing of said connection, supervisory signaling means for said connections, and means for confining the signals from said supervisory signaling means to the operator's position involved in the connection.

10. In a telephone system, an exchange, subscribers' lines in said exchange, operators' positions in said exchange, junction lines terminating in said exchange, means for establishing a connection between a junction line and any operator's position, means for preparing a connection between an answering operator's position and a desired subscriber's line, and means for thereafter removing said operator's position from the connection to the junction line and to the wanted subscriber's line and automatically completing the connection between the junction line and the wanted subscriber's line.

11. In a telephone system, an exchange, a subscriber's line in said exchange, operators' positions, junction lines terminating in said exchange, means for establishing a connection between a junction line and an operator's position, a registering mechanism for extending connections to a wanted subscriber's line, and means including an operator's dial for transmitting impulses to said registering mechanism to extend a connection to a wanted subscriber's line and for thereafter connecting said wanted line automatically to the junction line independently of said operator's position.

12. In a telephone system, an exchange, subscribers' lines terminating in said exchange, operators' positions, junction lines terminating in said exchange, means for establishing connections from junction lines to an operator's position, means for dialing the number of the wanted subscriber's line from said operator's position and for automatically disconnecting said position from the connection to the junction line, a signal operative at the position of the operator who answers the incoming call over a junction line, means for maintaining said signal actuated after the operator has dialed the number of the wanted line, means for again connecting the operator's position with the incoming junction line until the moment when the connection between the incoming junction line and wanted subscriber's line is completed, and means for thereafter disabling the signal and removing said operator's position from the connection in response to the wanted subscriber answering the call.

13. In a telephone system, an exchange, subscribers' lines in said exchange, operators' positions in said exchange, means for establishing a connection between any two subscribers' lines, means for establishing a connection from any subscriber's line to any operator's position, automatic stepping switches, and means whereby said automatic stepping switches are momentarily actuated by said means for establishing a connection between any two subscribers' lines and means for establishing a connection from any subscriber's line to any operator's position to aid in the establishing of said connections.

14. In a telephone system, an exchange, subscribers' lines in said exchange, operators' positions in said exchange, junction lines outgoing from said exchange, means for establishing a connection directly from a subscriber's line to an idle junction line, means for establishing a connection from a subscriber's line to an operator's position, means for establishing a connection to an idle junction line from an operator's position, and means for thereafter effecting a junction between the connection extended from the subscribers' lines to the operator's position and the junction line seized by said operator's position and for eliminating the operator's position from said last established connection.

15. In a telephone system, an exchange, subscribers' lines in said exchange, operators' positions in said exchange, junction lines outgoing from said exchange, means for establishing a connection directly from a subscriber's line to an idle junction line, means for establishing a connection from a subscriber's line to an operator's position, means for establishing a connection to an idle junction line from an operator's position, means for thereafter effecting a junction between the connection extended from the subscribers' lines to the operator's position and the junction line seized by said operator's position and for eliminating the operator's position from said last established connection, and means for thereafter transmitting a supervisory signal to said operator's position and over said junction line.

16. In a telephone system, an exchange, subscribers' lines in said exchange, operators' positions in said exchange, junction lines incoming to said exchange, means for establishing connections from the operators' positions to incoming junction lines, means for establishing connections from operators' positions to subscribers' lines, and signaling means at an operator's position for indicating the presence of a call incoming over a junction line if said operator is engaged in a local connection and for indicating the presence of a call from a subscriber's line if said

operator is engaged in a connection with a junction line.

In witness whereof: we hereunto subscribe our names this 5th day of March 1931.

5   WILLIAM HATTON.
RANSOM D. SPANN.
ERNEST J. ROUSSEAU.
FRIDTHIOF O. V. LARSEN.
